US00D535308S

(12) **United States Design Patent** (10) **Patent No.:** **US D535,308 S**
(45) **Date of Patent:** **** Jan. 16, 2007**

(54) **MEDIA DEVICE**

(75) Inventors: **Bartley K. Andre**, Menlo Park, CA (US); **Daniel J. Coster**, San Francisco, CA (US); **Daniele De Iuliis**, San Francisco, CA (US); **Richard P. Howarth**, San Francisco, CA (US); **Steve Jobs**, Palo Alto, CA (US); **Jonathan P. Ive**, San Francisco, CA (US); **Duncan Robert Kerr**, San Francisco, CA (US); **Shin Nishibori**, San Francisco, CA (US); **Matthew Dean Rohrbach**, San Francisco, CA (US); **Douglas B. Satzger**, Menlo Park, CA (US); **Calvin Q. Seid**, Palo Alto, CA (US); **Christopher J. Stringer**, Portola Valley, CA (US); **Eugene Antony Whang**, San Francisco, CA (US); **Rico Zörkendorfer**, San Francisco, CA (US)

(73) Assignee: **Apple Computer, Inc.**, Cupertino, CA (US)

(**) Term: **14 Years**

(21) Appl. No.: **29/257,238**

(22) Filed: **Mar. 31, 2006**

Related U.S. Application Data

(63) Continuation of application No. 29/220,038, filed on Dec. 23, 2004.

(51) **LOC (8) Cl. 14-03**

(52) **U.S. Cl. D14/496**

CLAIM

We claim the ornamental design for a media device, substantially as shown and described.

DESCRIPTION

FIG. 1 is a perspective view of a media device showing our new design;

FIG. 2 is an exploded perspective view thereof;

FIG. 3 is a front elevational view thereof;

FIG. 4 is a rear elevational view thereof;

FIG. 5 is an exploded front elevational view thereof, with the cap removed;

FIG. 6 is a left side elevational view thereof;

FIG. 7 is a right side elevational view thereof;

FIG. 8 is an exploded left side elevational view thereof, with the cap removed;

FIG. 9 is a top plan view thereof;

FIG. 10 is a bottom plan view, with the cap removed;

FIG. 11 is a bottom plan view thereof, with the cap connected; and,

FIG. 12 is a top plan view of the cap, showing it's inside.

1 Claim, 2 Drawing Sheets
